CAPSTAN

Filed May 17, 1927

Inventor:
Almon E. Norris,
By Emery, South, Janney & Kuray,
Atty.

UNITED STATES PATENT OFFICE

ALMON E. NORRIS, OF BROOKLINE, MASSACHUSETTS

CAPSTAN

Application filed May 17, 1927. Serial No. 191,998.

This invention relates to capstans of the class in which the driving mechanism for the head operates in an oil bath, in a chamber which is closed by the rotating head.

5 The invention will be best understood by reference to the following description, when taken in connection with the accompanying drawing of one illustrative embodiment thereof, while its scope will be more particularly pointed out in the appended claims.

In the drawing, the single figure shown is a central, vertical, sectional view of a capstan exemplifying the invention.

Referring to the drawing, and to the embodiment of the invention which is selected for exemplification, there is shown a capstan comprising a casing 4, presenting a base 5 surmounted by a head 6. The head is mounted to turn on upper and lower bearings 7 and 8, presented by a column 9 upstanding from and herein conveniently formed as an integral part of the base.

The base presents a wall 10, between which and the column 9 there is a chamber 11, having at its upper portion an annular opening 12. The head thus presents a closure for this opening, as it covers the entire space between the wall 10 and the column 9. The chamber is protected against the entrance of foreign matter by providing the head with a skirt 13, at least as large in diameter as the opening 12, and herein overlapping the latter. This skirt 13 and the wall 10 have confronting surfaces opposed end to end, and they are suitably constructed to exclude foreign matter, and to prevent the escape of oil, as by providing them with interjacent parts, in the present example inner and outer depending flanges 14 and 15 on the skirt, presenting between them an annular groove 16, which receives an upstanding flange 17 presented by the wall 10.

The depending flange 14 is provided with a beveled surface 18, and the upstanding flange 17 with a similar, but oppositely beveled surface 19. The first bevel tends to prevent the oil in the chamber 11 from creeping up into the joint presented by the adjacent surfaces of the flanges 17 and 14, while the second bevel forms an enlarged space or chamber, which tends to break the adhesion of

the oil, and to allow the latter to gravitate back into the casing. When, however, the capstan is operated at high speed for a long period of time, the heat generated by the driving mechanism within the chamber 11 is such as to expand the air therein. This tends to force oil out between the interjacent parts of the skirt 13 and the wall 10. Such leakage, however, is entirely prevented by the means presently to be described.

Herein, the head presents two hubs 20 and 21, turning on the upper and lower bearings 7 and 8, respectively. The head has an outer wall 22, connected to the hub 20 by a wall 23, and to the lower hub 21 by a wall 24. Between the walls 23 and 24, there is a chamber 25.

The head is driven by suitable mechanism, herein a worm gear 26, conveniently secured thereto as by cap screws 27 extending into the wall 24. This gear is driven by a worm 28. This driving mechanism is intended to run more or less completely submerged in a bath of oil in the chamber 11. The gearing, when run at high speed, generates considerable heat, and as there is little room in the chamber for expansion of the air, when the latter does expand to too great an extent, oil is likely to be forced out of the chamber between the confronting surfaces of the base and the head. This escape of oil is entirely prevented by providing means for venting the air space in the chamber 11 to the atmosphere, yet without in any way risking the possibility of water or other foreign substance reaching the chamber, and without the possibility of oil getting to the outside through the venting passages.

This is conveniently accomplished in the present example by providing the partition 24 with a passage 29, affording communication between the upper portion of the chamber 11 and the chamber 25, and by providing a further passage 30, affording communication between the chamber 25 and a passage 31 provided in the column 9. The passage 31 in the present example is in direct communication with the atmosphere through an opening 32 presented by an annular plate 33, which is secured to the column by screws

34, and thus holds the head in place on the column. The course taken by the air in travelling from the chamber 11 to the outer atmosphere is indicated by a series of arrows.

5 Having thus described one embodiment of the invention, but without limiting myself thereto, what I claim and desire by Letters Patent to secure is:

10 1. In a capstan, the combination of a base and a column, said base presenting an outer wall and said column presenting an inner wall, between which walls there is a lower chamber having at its upper portion an annular opening, said column presenting an opening leading to the atmosphere, a head mounted to rotate about said column, said head presenting a closure for said annular opening, and a wall above said closure, there being an upper chamber between said closure and said 15 wall thereabove, said closure being provided with a passage affording communication between said lower chamber and said upper chamber, and said inner wall being provided with a passage affording communication between said upper chamber and said opening leading to the atmosphere.

20 2. In a capstan, the combination of a rotatable head, means presenting a chamber, mechanism within said chamber for rotating said head, and conduit means for venting said chamber to the atmosphere and preventing the escape of lubricant therefrom.

25 3. In a capstan, the combination of a rotatable head, a base and a column providing a support for said head and presenting a chamber having at its upper portion an opening which is closed by said head, said head having a hub, an outer wall, and a web connecting said hub and outer wall, said web being provided with an opening affording communication between said chamber and the space above said web, said column presenting a conduit leading from said space to the outer atmosphere, and mechanism within 30 said chamber for rotating said head.

40 4. In a capstan, the combination of a base presenting a chamber having an opening at its upper portion, a column upstanding within said chamber and extending upwardly 45 therebeyond and presenting upper and lower bearings, a head closing said opening and having upper and lower hubs about said upper and lower bearings, an outer wall, and upper and lower webs connecting said hubs to said outer wall, said lower web having a passage affording communication between said chamber and the space between said webs, said column having a passage which extends laterally from said space and thence lengthwise 50 of the axis of said column to the outer atmosphere, and mechanism within said chamber for rotating said head.

In testimony whereof, I have signed my name to this specification.

55 ALMON E. NORRIS.
